UNITED STATES PATENT OFFICE.

WILLIAM BUCCUTO, OF SALEM, NEW JERSEY.

VENTILATING FAN.

Application filed May 19, 1924. Serial No. 714,369.

To all whom it may concern:

Be it known that I, WILLIAM BUCCUTO, a citizen of the United States, residing at Salem, in the county of Salem and State of New Jersey, have invented new and useful Improvements in Ventilating Fans, of which the following is a specification.

In carrying out the present invention it is my purpose to provide a ventilating fan and driving means therefor which will be found especially useful in the cars of subway trains to cause the circulations of air in such cars.

It is also my purpose to provide a driving means for ventilating fans by which the fan may be driven with a minimum expenditure of commercial power and which will embrace the desired features of simplicity, efficiency and durability.

Furthermore, I aim to provide a ventilating fan construction wherein the fan may be held against operation whenever desired or necessary and wherein the component parts will be so arranged and correlated as to reduce the possibility of derangement to a minimum.

With the above recited objects in view, and others of a similar nature, which will appear as the nature of the invention is more fully set forth, the invention consists in the construction, combination and arrangement of parts set forth in and falling within the scope of the appended claims.

In the accompanying drawings:

Figure 1 is a fragmentary sectional view through the roof of the car of a subway train, showing my improved ventilating fan installed therein.

Figure 2 is a bottom plan view of the same.

Figure 3 is a sectional view on the line 3—3 of Figure 1.

Figure 4 is a diagrammatic view showing the electric motor drive for the fan.

Figure 5 is a detailed side elevation showing a modified form of braking mechanism.

Figure 6 is a plan view of the same.

Referring now to the drawings in detail, 1 designates the top or ceiling portion of a subway car or other car that it is desired to ventilate by means of my improved apparatus, while 2 designates a housing bolted or otherwise secured to the under side of the top or ceiling 1. Extending through the housing 2 is a vertical shaft 3 and fastened to the upper end of the shaft 3 above

the top 1 of the car are propeller blades 4, while fixed to the lower end of the shaft 3 within the car and below the housing 2 are fan blades 5. As the car travels along the air impinges upon the blades 4 and so imparts rotary motion to the shaft 3, thereby revolving the fan blades 5 so that the fan continues to operate to ventilate the car as long as the latter is in motion, incident to the air striking the propeller blades 5 and revolving the latter.

Within the housing 2 is an electric motor 6 of any suitable construction connected in an electric circuit 7 including a suitable source of electrical energy and a switch 8. This motor 6 is connected with the shaft 3 in some suitable manner, and when energized acts to rotate the fan blades 5 independently of the propeller blades 4, thereby permitting the fan blades to be operated for ventilating purposes when the car is at a standstill.

At times it may be desired to hold the fan blades 5 against rotation under the action of the blades 4 when the car is in motion, and for this reason I provide a suitable brake mechanism. In the preferred form of my invention the brake mechanism embodies a brake drum 9 fixed to the shaft 3 immediately above the hub of the blades 5 and brake shoes 10—10 arranged upon opposite sides of the brake drum 9 and having their inner ends arranged in juxtaposition to the drum 9 to engage the latter and their outer ends fixed to vertical arms 11—11, respectively, that depend from the top or ceiling 1. In the present instance the upper ends of the arms 11 are pivotally connected with blocks 12, respectively, that are fastened to the under side of the top 1, while to the lower end of one of the arms 11 is pivotally fastened one end of a rod 13, the other end of which extends through a slot formed in the lower end of the other arm 11. Rotatably mounted in the free end of the rod 13 is a cam 14 provided with a lever 15 connected with one end of a cord 16 or other operating element. Thus, when the cord 16 is pulled, the cam 14 is rotated

to swing the arms 11—11 toward each other through the medium of the rod 13, thereby moving the brake shoes 10—10 into engagement with the drum 9 to hold the shaft 3 against rotation under the action of the fan blades 4.

In my present construction the inner

ends of the brake shoes 10—10 are formed with slots 17 through which extend pins 18 fastened to the bottom of the housing 2 and surrounding these pins 18, respectively, 5 are springs 19 that are interposed between the lower end of the housing 2 and the upper surfaces of the brake shoes 10, thereby maintaining the brake shoes in proper positions with respect to the drum 9.

10 In the modified form of the invention illustrated in Figures 5 and 6 of the drawings I dispense with the brake shoes 10—10 and the arms 11 and associated parts and employ a brake mechanism which embodies 15 a drum 20 fixed to the shaft 3 and a brake band 21 surrounding the drum 20. This band 21 is pivoted at one point, as at 22, and at a diametrically opposite point is formed with outturned lugs 23—24. To the 20 lug 23 is pivoted one end of a pin 25, the other end of which extends through the slot formed in the lug 24. Upon the last mentioned end of the pin 25 is rotatably mounted an operating cam 26 provided with a 25 lever 27 which, in turn, is connected with an operating cord 28 embodying two runs 29 and 30, respectively, this cord 28 being trained over a pulley 31. Thus, when the run 29 of the cord 28 is turned in the direction of the arrow in Figure 6, the cam 26 is operated to expand the brake band 21 and so release the drum 20, whereas when the run 30 is pulled in the direction of the arrow in Figure 6 of the drawings the cam 26 is 30 operated to contract the band 21 about the drum 20, thereby holding the shaft 3 against rotation.

35 While I have herein shown and described one preferred form of my invention by way 40 of illustration, I wish it to be understood

that I do not limit or confine myself to the precise details of construction herein described and delineated, as modifications and variations may be made within the scope of the claims and without departing from 45 the spirit of my invention.

Having thus described the invention, what is claimed as new, is:—

1. In ventilating apparatus for motor vehicles, a vertical shaft extending through 50 the top of the vehicle, fan blades on the inner ends of said shaft, propeller blades on the outer end of said shaft, rotatable by the action of the air in the travel of the vehicle to rotate the fan blades within the vehicle, a 55 housing fastened to the under side of the top of the vehicle and encasing the major portion of said shaft and a motor within said housing connected to said shaft to drive the latter independently of said propeller 60 blades.

2. In ventilating apparatus for motor vehicles, a vertical shaft extending through 65 the top of the vehicle, fan blades on the inner ends of said shaft, propeller blades on the outer end of said shaft, rotatable by the action of the air in the travel of the vehicle to rotate the fan blades within the vehicle, a housing fastened to the under side of the top of the vehicle and encasing the 70 major portion of said shaft, a motor within said housing connected to said shaft to drive the latter independently of said propeller blades, and brake mechanism associated with the inner end of said shaft immediately 75 below said housing to hold the said shaft against rotation.

In testimony whereof, I affix my signature.

WILLIAM BUCCUTO.
